UNITED STATES PATENT OFFICE.

GEORGE T. BROWN, OF BALTIMORE, MARYLAND, ASSIGNOR OF ONE-HALF
TO JAMES D. BROWN, OF BALTIMORE, MARYLAND.

TUBULAR LANTERN.

SPECIFICATION forming part of Letters Patent No. 727,892, dated May 12, 1903.

Application filed July 16, 1902. Serial No. 115,840. (No model.)

To all whom it may concern:

Be it known that I, GEORGE T. BROWN, of Baltimore, in the State of Maryland, have invented certain new and useful Improvements 5 in Tubular Lanterns; and I hereby declare that the following is a full, clear, and exact description thereof, reference being had to the accompanying drawings, which form part of this specification.

This invention is an improvement in tubular lanterns; and its objects are, first, to improve the construction of the tubular frame, particularly the uprights or side tubes thereof; second, to improve the connection of the 15 bell to the uprights, and, third, to improve the construction of the globe-holder and connection thereof with the frame.

To these ends the invention consists (a) in the novel construction of the side tubes or 20 uprights, (b) in novel means for securing the bell to the uprights, (c) in novel means of connecting the bail to the frame, (d) in the novel construction of the globe-holder, and (e) in minor novel details, combinations, and 25 constructions of parts hereinafter described.

In the accompanying drawings I have illustrated a complete tubular lantern embodying my invention.

Figure 1 is a front view of the complete 30 lantern with one upright of the frame in section. Fig. 2 is a side view thereof. Fig. 3 is a detail top plan view of the globe and globe-holder; Fig. 4, a horizontal transverse section looking upward on line 4 4, Fig. 1. Fig. 5 is 35 a detail view of the clip connection between the upright and font. Fig. 6 is an enlarged sectional view of such connection. Figs. 7 and 8 are magnified views on line 7 7 and 8 8, Fig. 1. Fig. 9 is a detail view illustrating the 40 mode of attaching the bell to the uprights.

The font A may be of any suitable construction and provided with a collar a, on or to which the burner may be attached in any preferred manner. The burner B may also 45 be of any desired construction, although I prefer to use burners like those shown and described in my application, Serial No. 114,798, filed July 8, 1902.

Exterior to collar a is an air-chamber, 50 formed within the annular ring A', which is secured to the top of font concentric to the

collar, and to this ring A' at diametrically opposite points are secured the lower ends of the air-tubes or uprights C, which are of novel construction and are, preferably, also 55 secured at their lower ends to the top of font to give greater strength and rigidity to the lantern-frame, which comprises the font, uprights, and bell. As shown in Figs. 1 and 2, the lower ends of the uprights may be 60 firmly attached to the font by means of the metallic clips b, which are provided with bridge portions fitted over the lower ends of the uprights adjacent to the ring and having flattened ends b', which can be soldered to 65 the top of font, and having also openings in their outer walls b² for the passage of the lower ends of uprights, said walls b² having depending portions b³, which are adapted to enter slit a² in the top of font and are bent 70 under and against the top of font and secured by soldering, thus forming a very secure connection between the uprights and font and strengthening the font at the part subjected to most strain.

The uprights C have lower inwardly-curved ends C', attached to the font or air-chamber, or both, as shown, and upper inwardly-curved ends C², attached to the tubular stem D', to the lower end of which the bell D is centrally 80 attached. Each upright is formed complete in one piece from a strip of sheet metal, preferably tin, as follows: A strip of suitable length and width is first bent into a tube of desired diameter, preferably with a lapped 85 seam. Then the tube is firmly held in a suitable clamp, and the tube ends are bent into proper shape, as at C' C², by means of a suitable mandrel having a hole of a diameter equal to that of the tube and of a curvature 90c corresponding to that desired for the end of tube. A suitable core may be provided in the mandrel to prevent collapse of the end of the tube during the bending operations. I do not claim herein the mechanism for bending the tube, and therefore consider it needless to illustrate such mechanism, as it may readily be constructed by those skilled in metal bending. The tubular uprights thus formed are smooth throughout both at straight 100 portions and in the bends, forming a continuous smooth bent tube, as illustrated in the

drawings, without corrugations or transverse joints or slits in the metal at the bends. Preferably the lap-joint in the tube is kept at the inner side of bends, so that the uprights in the frame appear to be made from drawn-metal tubes. After the uprights are formed, as described, they are redipped in tin, which binds the lap-joint securely and gives a fine finished appearance to the uprights.

10 The stem D' is hollow, but closed at top, so as to cause the heated air to return through the tubes to the combustion-chamber. The bell D is of ordinary appearance and firmly attached to the lower end of the stem, so as to direct the hot air thereinto. It is also preferably of a diameter equal to the distance between the uprights at the lower end of the stem and is preferably rigidly attached to the uprights.

15 As shown, I employ two wires E, each of which is bent centrally into a figure-8 loop, from which the ends e^2 of the wire extend in opposite directions and are attached to the edge of the bell D, which is bent thereover, as shown at d, thus firmly attaching the loops to the bell at diametrically opposite points, while the wires serve to stiffen the edges of the bell. The inner bends e of the loops in wires E are slipped over the uprights C before the latter are finally attached to the stem or font, and after the bell and uprights are set in proper position the outer bends e' of the 8-loops in wires E are bent into a vertical position, as shown in Fig. 1. This bending

20 twists the wire at the center of the loop, lessening the diameter of the inner bend thereof and causing it to tightly bite the upright and bind the bell securely thereto. After the bends e' are bent into vertical position they constitute eyes for the attachment of the bail F, which is connected thereto, as shown in the drawings. The wires E thus constitute the means for stiffening the bell for locking it to the uprights and for connecting the

25 bail to lantern-frame. The 8-loop wires could be used for attaching the bails to the uprights in lanterns having vertically-movable globes and bells. As is obvious, in the latter case the loops would not perform the functions of

30 stiffening bell or fastening it to the uprights.

The globe-holder is composed of the base-plate G, from which rise opposite vertical wires G', connected a short distance above the base by a ring G². The upper ends of the wires G are unattached; but each is provided with a globe-engaging device which is preferably formed integral with the vertical wire by bending it as shown, so as to form a loop g, having a horizontal curved bar g', connect-35 ed at its ends by outwardly and downwardly bent portions with the vertical wires G'. The loop is so bent that bar g' will rest upon and engage the bead h at the upper end of the globe H and will also partly encircle the globe, and, as shown, the bar g' extends about one-quarter around the globe. The two opposite loops clasp the globe firmly and hold it se-

curely to the plate, while permitting it to be removed by springing the loops g apart. The holder is preferably connected to the font, as described in my application, Serial No. 114,797, filed July 8, 1902, being hinged at one side to a loop I, fixed to the font, and a catch i being attached to the opposite side of base-plate and engaging a loop I' on the font opposite loop I. When catch i is released, the globe-holder tilts back out of the frame, as indicated in dotted lines, Fig. 2, and the globe can be readily removed or replaced or the burner lighted or extinguished.

80 The lantern shown and described is strong, simple, and economical in cost.

It should be understood that the tubular uprights which I have described could be used in any kind of lantern, whether the frame be rigid or tilting or whether the globe be tiltable or vertically movable, and therefore I do not restrict myself to the employment of the novel tubes or uprights in a rigid-frame lantern, nor is it essential that the globe-holder be used with the particular frame described, nor that the bell-fastening and bail-attaching loops be used with the particular frame or globe-holder described. Altogether they constitute a most efficient tubular lantern; but I wish to protect the various novel features of my lantern in all applications thereof.

Having thus described my invention, what I therefore claim as new, and desire to secure by Letters Patent thereon, is—

1. In a tubular-lantern frame, tubular side uprights each composed of a one-piece sheet-metal tube having its opposite ends bent on smooth unbroken curves, substantially as described.

2. An upright for tubular-lantern frames composed of a one-piece sheet-metal lapped-joint tube, having both its ends bent inwardly on smooth unbroken curves, and connected by a straight portion, substantially as described.

3. A frame for tubular lanterns composed of side uprights provided with curved ends and each composed of a one-piece lapped sheet-metal tube with ends bent on smooth curves and the lap-joint retinned, substantially as described.

4. For a tubular-lantern frame, an upright composed of a one-piece sheet-metal lapped-joint tube, having a straight intermediate portion and both ends bent inwardly on smooth unbroken curves, the lap-joint being at the inner sides of the bends, substantially as described.

5. A tubular-lantern frame composed of a base, a bell-tube, and side uprights connecting the same, each consisting of a one-piece sheet-metal tube bent at its ends on unbroken curves and respectively connected to the bell-tube and base, substantially as described.

6. A tubular-lantern frame composed of a base, a bell-tube, and tubular uprights rigidly connecting the same, each of said uprights

consisting of a single piece of metal bent into tubular form, such tube being bent at its ends on unbroken curves and connected to the base and bell-tube, and a bell connected to the bell-tube and uprights, substantially as described.

5 7. A tubular-lantern frame comprising the font having an air-chamber, a bell-tube, tubular uprights having their lower and upper ends curved inwardly, each upright consisting of a one-piece lapped-joint tube bent inwardly at both ends and rigidly connected to the air-chamber and to the tube respectively, and a bell connected to the tube and uprights, substantially as described.

10 8. In combination, the lantern-frame, and a bell fixedly secured to the uprights of the frame by twisted wire loops, substantially as described.

9. In combination, the lantern-frame, and a bell secured to the uprights of the frame by twisted wire loops, each of said loops having two bends, respectively embracing the uprights and forming bail-attaching eyes, substantially as described.

15 10. In combination, the uprights of a lantern-frame, a bell, and opposite wires attached to the edges of the bell, having loops formed with two bends, one bend of each loop embracing the adjacent upright, the other bend being turned at right angles to the former to bind them to the uprights and form bail-attaching eyes, substantially as described.

11. A globe-holder for lanterns, comprising a supporting-plate, the wires rising therefrom and attached thereto and independent opposite globe-engaging loops, respectively attached to the upper ends of said wires, substantially as described.

15 12. A globe-holder for lanterns, comprising a supporting-plate, opposite wires rising therefrom and attached thereto, opposite independent globe-engaging loops respectively attached to the upper ends of said wires, and a ring connecting the wires below the loops, substantially as described.

13. In a lantern, the combination of the frame, the globe-support connected thereto, comprising a base-plate, opposite vertical wires rigidly attached to the base-plate, and opposite independent curved globe-engaging loops respectively attached to the upper ends of said vertical wires adapted to clasp the globe and hold it removably to the base-plate, substantially as described.

14. In a lantern, the combination of the frame, and the globe-support connected thereto, comprising a base-plate, opposite vertical wires rigidly attached to the base-plate, a ring connecting the wires above the base-plate, and opposite disconnected curved globe-engaging loops on respectively the upper ends of said vertical wires and adapted to clasp the globe and hold it removably to the base-plate, substantially as described.

15. In combination, in a tubular lantern with the frame, and bail, the wire loops each having two bends one bend locked to the uprights and the other bend forming the bail-attaching eyes, substantially as described.

16. In a tubular lantern the combination of the font, the uprights, and the clips attached to the lower ends of uprights and soldered to top of font, said clips having a tongue on their front sides entering the font and secured therein, substantially as described.

17. In a tubular lantern the combination with the font having a ring, and the tubular uprights connected to said ring, of the clips crossing the lower ends of uprights and soldered to the font, and provided with tongues passing through slits in the top of font and fastened to the underside of the font-top, substantially as described.

In testimony that I claim the foregoing as my own I affix my signature in presence of two witnesses.

GEORGE T. BROWN.
